UNITED STATES PATENT OFFICE.

LOUIS L. HINSCH, OF COSHOCOTON, OHIO, ASSIGNOR TO THE ADMIRAL TIRE & RUBBER COMPANY, OF COSHOCOTON, OHIO, A CORPORATION OF OHIO.

DESIGN FOR AN AUTOMOBILE TIRE CASING.

Application filed May 22, 1924. Serial No. 9,689. Term of patent 7 years.

To all whom it may concern:

Be it known that I, LOUIS L. HINSCH, a citizen of the United States, residing at Coshocton, in the county of Coshocton and State of Ohio, have invented a new, original, and ornamental Design for an Automobile Tire Casing, of which the following is a specification, reference being had to the accompanying drawings, forming a part thereof.

Figure 1 is a perspective view of a tire

casing embodying my invention; Fig. 2 is an enlarged transverse sectional view through the same, the plane of the section being indicated by the line 2-2 of Fig. 3; Fig. 3 is a plan of a portion of the casing made in accordance with my design.

I claim:

The ornamental design for an automobile tire casing substantially as shown.

LOUIS L. HINSCH.
